METHOD OF RECLAIMING ELECTRIC LAMPS
AND MECHANISM THEREFORAlbert M. Butler, Danvers, Mass., assignor, by
mesne assignments, to Corning Glass Works,
Corning, N. Y., a corporation of New York

Application January 31, 1934, Serial No. 709,157

5 Claims. (Cl. 176—7)

This invention relates to the reclaiming of burned-out electric lamps and consists in a novel method of treating the bulbs of such lamps so that they may be reformed for reuse without loss of material. It also includes within its scope 5 a novel mechanism for carrying out the method of the invention.

In one aspect the present invention consists in a further development of the commercial method 10 of reclaiming electric lamps disclosed in U. S. Letters Patent No. 1,920,528, granted August 1, 1933, to Butler and Lane, and in accordance with 15 which the neck of the burned-out bulb is severed on a line which is usually located above the line of juncture between the bulb and the flare of the filament mount. In following the method of that 20 patent, therefore, a small amount of material is lost from the end of the neck of the bulb. This is not usually objectionable unless the bulb is subjected to repeated reclaiming operations, but 25 under those conditions the bulb may be eventually shortened and the capacity of its chamber consequently reduced. An object of the present invention is to make available a commercially practicable method whereby the reclaiming operation 30 may be effected without loss of material from the bulb so that its original shape may be exactly reproduced, if desired, or surplus material provided to facilitate reshaping of the bulb and resealing of a new mount therein.

In carrying out the method of the present invention, the filament mount is parted or severed on a line located above or within the line of juncture between the bulb and the flare of the mount 35 so that the flare portion of the mount, or a rim of material including the flare portion of the mount, is left as an integral part of the neck of the bulb. In other words, the mount is severed along a line or in a zone entirely included within 40 the body of the mount so that the neck of the bulb is not only left intact but is provided with an inturned rim of additional material which may subsequently be shaped into the neck of the bulb. The replenishment of the neck material 45 in this manner facilitates reshaping of the neck of the bulb without loss of length and permits the manufacturer to reproduce the original shape of the bulb for as many reclaiming operations as may be desired.

50 The precise manner of severing or parting the mount is of secondary importance only. This may be successfully accomplished by directing a fine cutting flame obliquely against the interior wall of the hollow mount or by cutting or scoring 55 the mount by means of a sand blast, or by crack-

ing or breaking the mount by means of a circular heated wire introduced against its annular wall, or by various other expedients which will suggest themselves to those skilled in the art. It is essential only that the mount be cut along a line which will leave at least some of the material of the 5 rim of the mount sealed to the neck of the bulb.

Since the method and mechanism of my invention is designed particularly for the treatment of tipless or base-exhausted electric lamps, 10 it becomes important to deal with the exhaust stem of the lamp which is located within the mount. This may be broken off to admit atmospheric pressure to the bulb prior to the step of severing or parting the mount and, if it is desired 15 to preserve a portion of the stem for future use, this may be done by protecting the end of the tube by any suitable means from the severing flame or other medium. In this connection, an important feature of my invention consists in a 20 tubular member designed for engaging and protecting the exhaust stem of a lamp and being provided with stop means for limiting or determining the position of the bulb with respect to the tubular member. The latter may be utilized 25 as a flame nozzle or a sand blast nozzle, or as a mount for a heating or chilling medium. For example, the tubular member may carry a circularly-disposed wire adapted to be electrically heated and the insertion of the tubular means 30 into the mount and, consequently, the location of the severing line may conveniently be determined by such stop means. It is believed that a stem protecting member of this character has never before been used with the function of 35 presenting a locating and severing instrumentality within the mount of an electric lamp.

It will be understood that in severing or parting the mount as above outlined, the opening 40 formed in the bulb is in the first instance of insufficient size to permit the removal of the severed portion of the mount. Accordingly, it is proposed to reshape the neck of the bulb and to enlarge 45 the opening thereof after the severed portion of the mount has been allowed to drop down inside the bulb and while it remains therein. The operation of reshaping the neck of the bulb preparatory to receiving a new mount enlarges the opening of the bulb to such an extent that the severed portion of the mount may thereafter be 50 readily removed.

These and other features of the invention will be best understood and appreciated from the following description of several ways in which it may be practiced and appropriate alternative mech- 55

anisms, selected for purposes of illustration and shown in the accompanying drawing, in which

Fig. 1 is a sectional view, on an enlarged scale, of a burned-out electric lamp in position to have its mount severed by a hot wire mechanism;

Fig. 2 is a similar view, on a smaller scale, suggesting the use of a cutting flame for parting or severing the mount or for heating it preparatory to local chilling;

Fig. 3 is a fragmentary view showing a portion of a bulb with chilling mechanism in position for severing or parting the mount;

Fig. 4 is a sectional view illustrating the step of reshaping the neck of the bulb after the mount has been parted or severed;

Fig. 5 is a similar view showing a form of nozzle which may be employed either for sand blast or cutting flame; and

Fig. 6 is a sectional view on the line 6—6 of Fig. 5.

In the drawing there is shown, more or less conventionally, a burned-out electric lamp comprising the bulb 10, into the neck of which is sealed a hollow mount 12 having a flange or flare portion 14. From the inner end of the mount projects a filament-supporting stem or post 16 and upon the end of this post is mounted a filament 18. The mount includes an exhaust stem 20 which extends axially and concentrically in the mount and is curved at its inner end, opening through the wall of the mount into the interior of the bulb. It will be understood that in the figures of the drawing the metallic cap which usually encloses the neck end of the bulb is assumed to have been removed and the exhaust stem 20 to have been broken for the purpose of admitting atmospheric pressure to the interior of the bulb. Lead-in wires 22 are shown as passing through the body of the mount and sealed into the inner end thereof. The lead-in wires and the exhaust stem 20 may be broken at any convenient point so that they will not interfere with the mechanism to be used in carrying out the method of my invention.

Referring first to Fig. 1, which illustrates the hot wire for locally heating the mount, a tubular member 40 is employed which is equipped at its lower end with a block 42 of insulating material shaped at its outer face to correspond approximately with the contour of the end of the lamp. It is herein shown as provided with an annular groove or recess to receive the flare 14 of the mount and with an annular projecting portion 44 having a passage therein of the proper diameter to receive telescopically the end of the exhaust stem 20. Partially imbedded in the outer wall of the projecting portion 44 is a circular turn of wire 46 and this extends, through suitable leads, to a service line 48 by which a heating current may be supplied to the wire 46 when it has been properly positioned with respect to the mount 12, as shown in Fig. 1. When the wire 46 is thus intensely heated and engaged with the inner wall of the mount about a line of contact, the effect is locally to heat the mount in a narrow zone coinciding with the position of the wire 46. As shown in Fig. 1, this is located at substantially the point where the cylindrical wall of the mount merges into the outwardly-extending flare but this point may be located as desired to fit the requirements of the particular bulbs presented for treatment. As shown in Fig. 1, the end of the exhaust tube 20 projects somewhat into the passage of the member 42 and the lead-in wires 22 are represented as having been cut so that they lie entirely out of

contact with the projecting portion 44 of the insulating member.

In Fig. 2 is suggested the use of a fine flame 32 for locally heating the mount. The flame is projected obliquely from the jet or nozzle 30 against the inner wall of the mount near the inner edge of the flare 14. In this instance, the bulb 10 is suitably supported and rotated while being subjected to the action of the flame 32, and the latter is effective after a few revolutions of the lamp to heat the mount so that it may be readily broken in subsequently chilling. In Fig. 4, the bulb is represented as in the condition which it presents immediately upon the completion of the severing operation, and from this it will be seen that a substantial portion of the flare of the mount remains intact as an annular rim extending inwardly from the periphery of the neck.

In Fig. 3 is suggested another alternative mechanism for performing the severing or parting operation upon the mount. In this instance, a stem or spindle 60 is provided with head 62 having an annular chamber for a cooling medium and from the head projects a tapered chilling tool 64. The latter is shaped to enter the annular space within the mount 12 and is provided with a tubular passage 66 in its end designed to receive telescopically the end of the exhaust stem 20 of the lamp. The chilling tool 64 is maintained at a relatively low temperature by circulation of a cooling medium through the head 62 and is designed to be brought into contact with the inner wall of the mount 20 after the latter has been heated to some extent. The sudden contact of the cold chilling tool 64 with the heated glass of the mount causes the mount to break accurately about the line of contact.

In Fig. 5 is shown a tubular nozzle 50 having an annular chamber 52 and provided with radial arms 54 which serve as a limit stop to determine the operative position of the nozzle with respect to the end of the mount of the lamp. The nozzle is provided with a tubular projection or sleeve 56 designed to enclose the end of the exhaust stem 20 of the lamp and protect it during the severing operation as well as accurately to center the nozzle. The annular passage 52 is closed by a ring having one or a series of obliquely-disposed passages 58 therein for directing a flame or a sand blast against the inner wall of the mount about the line upon which it is to be parted or severed. Substantially this form of nozzle may be employed either to direct fine sand under high pressure against the wall of the mount or to direct a series of fine cutting flames thereagainst. In either case, it is desirable to support the lamp for rotation during the step. In adapting the nozzle for a sand blast, preferably only a single passage 58 is employed.

As herein suggested, it is desirable to carry out the severing or parting step while the lamp is held in inverted position so that as soon as the body of the mount is parted from its flange the severed portion of the mount may drop into the bulb in position entirely to clear the opening. The bulb 10, as suggested in Fig. 4, may now be presented to reshaping or reforming instrumentalities. To this end, the mount is supported for rotation in an inverted position and brought within range of a jet 70 or a series of jets which play upon the end of the neck and the unsevered portion of the flare until these are brought to a plastic condition. Prior to or during the heating operation, a suitable reforming tool, such as the curved bar 74, may be introduced into the bulb.

As herein shown, this is mounted in the lower end of an operating rod 12. The rod 12 is actuated, by mechanism not herein shown, to move the reforming bar slowly upwardly as the bulb 10 is revolved, thereby shaping or spinning the plastic material of the flare 14 and of the end of the neck into the cylindrical shape indicated by dot and dash lines in Fig. 4. As will be apparent, the effective opening of the bulb is thus enlarged to an extent permitting ready removal of the severed portion of the mount therefrom and advantage may be taken of this step to shape the end of the neck accurately for the reception of the flare of a new mount to be subsequently sealed thereto.

Having thus described my invention, what I claim as new and desire to secure by Letters Patent is:

1. A method of reclaiming electric lamps and adding material to the neck of the bulbs, characterized by the steps of heating the hollow mount of the lamp in a zone inwardly of its line of juncture with the neck of the bulb, and cutting off the mount without disturbing its position in the bulb in a line leaving a rim attached to the neck.

2. A method of reclaiming electric lamps, characterized by the steps of heating the hollow mount of the lamp by a flame directed obliquely against its inner wall, and cutting off the mount

above its line of juncture with the neck of the bulb while the mount remains in place within the bulb.

3. A method of reclaiming electric lamps, characterized by the steps of cutting the mount inwardly of its line of juncture with the neck of the bulb while the mount remains in place within the bulb, and replenishing the material of the bulb from that portion of the mount remaining attached thereto.

4. A method of reclaiming electric lamps, characterized by the steps of cutting the mount inwardly of its line of juncture with the neck of the bulb while the mount occupies its original position in the bulb, enlarging the opening in the bulb to permit removal of the severed portion of the mount, and replenishing the material of the neck from that portion of the mount remaining attached thereto.

5. A method of reclaiming electric lamps, characterized by the steps of cutting the mount inwardly of its line of juncture with the neck of the bulb, dropping the severed portion of the mount down inside the bulb, and simultaneously enlarging the opening of the bulb to permit removal of the severed portion of the mount and reshaping the neck to include the unsevered portion of the mount.
